BATHROOM CABINET

Bernard Berger, Chicago, Ill., assignor to National Steel Cabinet Company, Chicago, Ill., a corporation of Illinois

Application August 27, 1957, Serial No. 47,518

Term of patent 14 years

(Cl. D4—3)

Fig. 1.

Fig. 2.

Fig. 3.

Fig. 4.

Fig. 1 is a front elevational view of a bathroom cabinet embodying my new design.

Fig. 2 is a top plan view thereof.

Fig. 3 is an elevational view of one of the two identical sides thereof.

Fig. 4 is a sectional view on an enlarged scale taken on line 4—4 of Fig. 1, said sectional view being identical as to all four sides thereof.

The dominant portions of my design are shown in full lines.

I claim:

The ornamental design for a bathroom cabinet, substantially as shown and described.
